DESIGN FOR A SMOKING STAND OR THE LIKE

Alvin W. Nichols, Camden, N. J.

Application November 25, 1938, Serial No. 81,358

Term of patent 14 years

To all whom it may concern:

Be it known that I, Alvin W. Nichols, a citizen of the United States, residing at Camden, in the county of Camden and State of New Jersey, have invented a new, original, and ornamental Design for a Smoking Stand or the Like, of which the following is a specification, reference being had to the accompanying drawing, forming part thereof.

I claim:

The ornamental design for a smoking stand or the like, as shown.

ALVIN W. NICHOLS.
